Attn:

UNITED STATES PATENT OFFICE.

JOHN SAMUEL HEIZER, OF RUSHVILLE, INDIANA.

APPARATUS FOR WARMING THE UPPER ROOMS OF BUILDINGS.

SPECIFICATION forming part of Letters Patent No. 291,510, dated January 8, 1884.

Application filed June 30, 1883. (No model.)

To all whom it may concern:

Be it known that I, JOHN S. HEIZER, a citizen of the United States, residing at Rushville, in the county of Rush and State of Indiana, have invented certain new and useful Improvements in Apparatus for Warming Upper Rooms in Buildings, of which the following is a specification, reference being had therein to the accompanying drawings.

10 My invention relates to apparatus for warming the upper rooms of buildings; and it consists in certain improvements therein, as hereinafter described and claimed, the object of the invention being to utilize the escaping 15 heat in the flues of chimneys by retarding its upward passage to a certain extent and causing its radiation and passage into upper rooms.

In the accompanying drawings, Figure 1 is 20 a vertical section, showing upper and lower rooms of a building and a chimney having my invention applied thereto. Fig. 2 is a perspective view of the box provided with flues herein described.

25 Referring to the drawings, A designates the upper, and B the lower, room of a building. C is the fire-place, and F the flue of the chimney. A metallic box, E, having flanges e, is inserted in an opening in the wall, fitting 30 therein, so that said box extends into the flue of the chimney and partly across the same. Within box E are vertical flues or drums a, extending from top to bottom and terminating in openings, so that said flues form passages 35 through said box for smoke. The box E opens to the room designed to be heated, and is provided with a hollow cover or stopper, D, having a handle, f, for the purpose of closing the

box when it is desired to shut off the heat from the room. Rearward of box E, and against 40 the opposite wall of the chimney, are secured deflecting-plates d', these being formed to incline forward, so as to turn the column of smoke and products of combustion against and under the box E. A deflecting-plate, d, is 45 also placed at the rear of the fire-place, and such may be fixed at intervals along the chimney-flue, as desired. By this construction, the passage of smoke and products of combustion up the flue F being considerably retarded, 50 the box E becomes thoroughly heated, and the stopper D being removed, a considerable amount of heat passes from the chimney into the room which would otherwise escape through the chimney. 55

Having described my invention, I claim—

1. A box having a front opening and provided with vertical flues or drums, substantially as shown, said box extending into and partially across the flue of a chimney, in combination with one or more deflecting-plates, d', secured to the opposite side of the flue, substantially as and for the purposes described. 60

2. In a room-heating device, the combination of the box E, having tubes or drums a, the closing cover or stopper D, the chimney or flue F, deflecting-plates d', fire-place C, and deflecting-plate d, all constructed and arranged substantially as set forth. 65

In testimony whereof I affix my signature in presence of two witnesses.

JOHN SAMUEL HEIZER.
